UNITED STATES PATENT OFFICE.

WILLIAM L. McDOWELL, OF PHILADELPHIA, PENNSYLVANIA.

IMPROVEMENT IN STOVES.

Specification forming part of Letters Patent No. 38,318, dated April 28, 1863.

To all whom it may concern:

Be it known that I, WILLIAM L. McDOWELL, of the city of Philadelphia, in the State of Pennsylvania, have invented a new and useful Improvement in Stoves; and I do hereby declare that the following is a full, clear, and exact description of the construction and operation of the same, reference being had to the accompanying drawings, making a part of this specification, in which—

Figure 1 is a central vertical section of the lower portion of a common cylindrical coal-stove having my improvement applied thereto, and Fig. 2 a plan view of the supplementary top plate of the base of the same, like letters indicating the same parts when in both figures.

In nearly all the stoves in common use, especially those having cast-iron fire-boxes or cylinders, the heat is permitted to radiate horizontally, and, the said cylinders being generally kept red-hot, there is consequently danger of their charring or "setting fire" to one's clothing or any other combustible substance in its vicinity. The stoves used in railroad-cars especially are generally subject to this very objectionable feature. To obviate this objection in a perfect manner and without preventing the required diffusion of the radiating heat through the air around the stove is the object of my invention.

It consists, substantially as hereinafter described and specified, in the employment of a perforated supplementary top plate, in connection with or at a short distance above the usual top plate of the base of a stove, so that it shall serve the purpose of supporting a ventilating or skeleton fender around near the outer side of the fire cylinder or box, and at the same time permit the fresh air to pass upward through it and the space around between the said fire cylinder or box and the fender.

My invention also consists, substantially as hereinafter described and specified, in making the fender of a series of deflectors consisting of short hollow frustums of cones, or other suitable forms, of sheet metal, and arranging them around the outer side of the fire cylinder or box so as to be supported together upon the said perforated supplementary top plate of the base, leaving sufficient spaces between the said deflectors and between the latter and the stove for the hot air to pass ob-

liquely outward and upward from the cylinder or fire-box into the surrounding external air.

In the drawings, A is the fire cylinder or box; B, the base of the stove; C, the perforated supplementary top plate of the base; and D D' D² D³ the deflecting fender-plates, supported upon the plate C.

The base and fire-box of the stove may be of any of the usual forms. The supplementary plate C has a series of holes or openings, c' c', through it for the upward passage of fresh air and a larger opening in its middle for the reception of the lower end of the cylinder or fire-box A, the latter, together with the plate C, being supported by the usual top plate of the base, and the said plate c' being cast so as to have suitably projecting or grooved portions to adapt it for fitting firmly upon the base B and for receiving and supporting the skeleton fender upon it, and at the same time allowing the fresh air to pass upward through its openings c', as indicated by the arrows 1 1 in Fig. 1.

The deflecting-fender consists of a series of sheet-metal plates, D D' D² D³, cut to such widths, lengths, and bent into such forms as will permit them to overlap each other about an inch, (more or less,) leaving spaces e e between them when the said plates are arranged and supported around the cylinder or fire-box, substantially as shown in Fig. 1. The bottom deflecting-plate, D, fits closely down upon the perforated supplementary top plate, c', while each of the other deflecting-plates rests upon brackets f f f, which are fixed to the respective plate beneath it, as seen in the same figure.

In the operation of this invention it will be seen that, the cylinder or fire-box being hot, fresh air will enter the openings c' c' of the plate C, and, passing upward, will become warmed and escape obliquely upward and outward through the several spaces e e between the deflecting-plates D D, and also, in part, through the top space, c', as indicated by the arrows 2 2 2 2 in Fig. 1, and that consequently all direct horizontal radiation of heat from the fire box or cylinder will be prevented, and also a perfect guard afforded against all danger of one's clothes or other combustible articles in the vicinity coming in contact with or of being scorched or inflamed by the heat thereof.

The construction and arrangement are sim-

ple, cheap, and easily applicable to any of the stoves in common use.

I do not intend to confine myself to the precise form and arrangement of the deflecting-plates D, as described, but to vary them as fancy may suggest—as, for instance, the plates may be made either straight or curved and arranged in vertical positions or spirally around the stove.

Having thus fully described my improvement and pointed out its utility, what I claim as new therein of my invention, and desire to secure by Letters Patent, is—

1. The employment of a perforated supple-

mentary top plate, c', in combination with the usual top plate of the base of a stove, substantially in the manner described, for the purposes specified.

2. The employment of a series of deflecting-plates, D D' D² D³, arranged and supported around the cylinder or fire-box of a stove, so as to operate in the manner described, for the purposes specified.

WM. L. McDOWELL.
